UNITED STATES PATENT OFFICE

MARCEL AUDIFFREN, OF GOLBEY, NEAR EPINAL, AND HENRI ALBERT SINGRÜN, OF EPINAL, FRANCE, ASSIGNEES TO AUDIFFREN REFRIGERATING MACHINE COMPANY, A CORPORATION OF NEW JERSEY.

REFRIGERATING APPARATUS.

1,155,780.

Specification of Letters Patent.

Patented Oct. 5, 1915.

Application filed May 27, 1912. Serial No. 699,866.

To all whom it may concern:

Be it known that we, MARCEL AUDIFFREN, a citizen of the Republic of France, residing at Golbey, near Epinal, France, and 5 HENRI ALBERT SINGRÜN, a citizen of the Republic of France, residing at Epinal, Vosges, France, have invented certain new and useful Improvements in Refrigerating Apparatus; and we do hereby declare the 10 following to be a full, clear, and exact description of the invention, such as will enable others skilled in the art to which it appertains to make and use the same.

This invention is directed to the development of refrigerating apparatus of that type in which a suitable material in the form of a saturated or approximately saturated vapor or gas is confined in a container, and is 15 in one portion of the container, acted upon mechanically to cause it to liquefy and lose potential energy in the form of heat which is transmitted to and dissipated by a medium outside that portion of the container, in order that the material within the 20 container may effect refrigeration of a medium surrounding another portion of the container by absorbing heat therefrom as it vaporizes within that part of the container.

While a number of materials may be used, 25 sulfur dioxide (SO_2) is eminently suitable, in view of its relatively low saturated vapor pressure at the ordinary temperatures to be met with, and in view of the fact that its critical temperature is above these ordinary temperatures; and it will be considered as the material used within the container hereinafter described.

Refrigeration by dissipating heat from material confined in one portion of a container in order that it may re-absorb heat from matter surrounding another portion of the container, is effected to the best advantage by compression of saturated vapor in one portion of the container and the conduction of the latent and mechanically generated heat from the compressed vapor to a medium outside that portion of the container, which medium may be water circulated in contact with the wall of that portion of the container, in order that the vapor may liquefy.

The difficulties attending the confining of approximately saturated vapor or gas for

long periods, under considerable pressure, in containers into which working parts are led 55 through stuffing boxes or their equivalents, have called for the production of the hermetically sealed type of refrigerating apparatus, a form of which is described and shown in U. S. Patent No. 551,107, granted December 10, 1895, to Marcel Audiffren, one of the above-named applicants, in which apparatus a compressor is placed within a hermetically sealed container and the complementary working parts of the compressor 60 are respectively connected with a weight which does not revolve and with the container which is rotated from without. In a second U. S. Patent No. 764,515, granted July 5, 1904, to the same inventor, a machine of the same type as shown and described is provided with a lubricating system. A third U. S. Patent No. 898,400 was granted September 8, 1908, to the present applicants, namely Marcel Audiffren and 70 Henri Albert Singrün, for improvements in a machine of similar type. The present improvements are illustrated and described in connection with a machine similar in many respects to those shown in the above-named 75 patents.

The present invention resides in improvements in the organization of the inclosed working parts and in the disposition and construction of the lubricating and distributing systems employed in a refrigerating machine of the hermetically sealed type, and in the organization and arrangement of the container, driving means and associated apparatus necessary to the efficient employment of the apparatus in effecting refrigeration, all as hereinafter more specifically set forth and particularly pointed out in the appended claims.

In order that the improvements constituting the invention may be defined and differentiated from the prior art, with exactness, we have illustrated in the accompanying drawings, a refrigerating machine embodying these improvements.

In the drawings: Figure 1 is an elevation showing the tanks and housings about the refrigerating machine in section; Fig. 2 is a section through the liquefying end of the dumb-bell container taken on the line 2—2 105 of Figs. 1 and 3; Fig. 3 is a section through

the liquefying end of the dumb-bell container taken on the line 3—3 of Fig. 2; Fig. 4 is a section through the liquefying end of the dumb-bell container taken on the line 4—4 of Fig. 3; Fig. 5 is a detail partly in section, of the pressure equalizing valve and its operating mechanism, taken on the line 5—5 of Fig. 3; Fig. 6 is a section through the vaporizing end of the dumb-bell container taken on the line 6—6 of Figs. 1 and 7; Fig. 7 is a section through the vaporizing end of the dumb-bell container taken on line 7—7 of Fig. 6; Fig. 8 is a section through the vaporizing end of the dumb-bell container taken on line 8—8 of Figs. 6 and 7; and Fig. 9 is a detail section of the collectors showing the surface of the liquid contained in the vaporizing end of the dumb-bell container, while the machine is in motion, taken on the line 9—9 of Figs. 6 and 7.

A dumb-bell shaped hermetically sealed container has two enlarged end portions A and B which are connected by a hollow shaft C. The enlargement A is herein termed the "liquefying end" and the enlargement B, the "vaporizing end".

The two enlargements A and B of the container are connected by a hollow shaft C. The enlargement A, as shown, is formed of two substantially hemispherical shells *a* and *a'*, while the enlargement B consists of two shells *b* and *b'* which together inclose a chamber of somewhat greater diameter than its thickness axially. A driving shaft D projects axially from the outer end of the shell *a'* of the liquefying end A and is provided with tight and loose pulleys *d* and *d'*, respectively, or equivalent driving connections, such as couplings for direct drive or friction elements.

The dumb-bell container is mounted to be rotated as a whole in bearings E and F located adjacent the walls of the liquefying end A, in which bearings the shafts C and D are respectively journaled.

The bearings E and F are supported upon the upper edges of the walls of a tank G, and the tank G is filled with cooling water to a level below the bearings and at which level a suitable amount of the surface of the liquefying end A of the container will be submerged. A hood G' is provided to confine and return to the tank the water which would be carried up and dashed about by the rotation of the container. When the tank G is mounted upon an icebox or other structure which directly incloses the refrigeration chambers, we preferably provide an insulation such as cork, or other suitable material, at *g* to prevent the conduction or radiation of heat from the tank G to the cooled structure. The water is preferably kept circulating through the tank G, a suitable quantity being constantly supplied

through a pipe *g'* when the machine is in operation and a like quantity drawn off through a pipe *g''*. In this way, the temperature of the cooling water in tank G is maintained substantially constant, such heat as is imparted to the water from the liquefying end of the container, escaping in the water which is drawn off and in what vapor may arise from the water in the tank G.

The hollow shaft C projects through an opening in the wall of a brine tank H which may contain freezing flasks I if desired and the vaporizing end B of the container is located in this tank with a proper amount of its surface submerged in brine or other suitable liquid with which the tank H is filled to a level just below the aperture through which the shaft C enters the tank. With the exception of those parts next to chambers intended to be cooled the tank H should be thoroughly insulated by walls packed with cork, mineral wool or other suitable material *h* against the conduction of heat to the brine from the surrounding air or objects.

In practical applications of the apparatus to refrigerators having compartments for cold storage it is, of course, necessary to shape and place the brine tank H with or without brine-circulating pipes in such manner that it will cool these compartments, convection of the liquid being utilized, and an infinite variety of arrangements with this purpose in view are possible.

The interior structure of the dumb-bell container and its contained parts will now be described in detail.

The hollow shaft C projects into the chamber within the liquefying end A of the container and is sufficiently stiff to support all of the working parts which are inclosed within the liquefying end A without requiring a support for its free end upon the shell *a'*.

At about the center of the liquefying end A an eccentric *e* is secured upon the hollow shaft C by a key *e'* which prevents rotation of the eccentric upon the shaft, and screw *e''* engaged with both the key *e'* and the eccentric *e* secures the eccentric against end-wise movement on the shaft C. Two castings J and J' are bolted together and hung loosely on the shaft C within the liquefying end A and these castings provide certain chambers, within one of which chambers *j* the eccentric *e* works. In this chamber *j* two double-acting cylinders *j'* are mounted to oscillate on trunnions. These cylinders *j'* are preferably arranged at an angle of 90° from one another (see Fig. 2) both being located below the shaft C. Each of the cylinders *j'* has a piston *c* connected rigidly to a piston rod *c'* which works through a long close bearing on one head of the cylinder and is rigidly connected to an eccentric *c''*

strap c^5 working on the eccentric c which imparts reciprocating movements to the pistons and oscillating movements to the cylinders when the container is revolved and the castings J and J' remain stationary. Each of the cylinders j' is provided with inlet ports j^2 at its opposite ends which emerge at flats on the side of the cylinder, which flats contact with like flats j^3 on the casting J' , and the ports j^2 are alternately registered by the oscillation of the cylinders with ports j^4 emerging from the said flats j^3 on the wall of the casting J' and communicating with a passageway j^5 which is always in open communication with the interior of the hollow shaft C .

In connection with the description we have found it convenient to consider the material used in the container as sulfur dioxide SO_2 and the vapor of the gas is drawn into the cylinders from the hollow shaft C through the passageway j^5 and ports j^4 and j^2 , then in registry, by the suction strokes of the pistons c^3 and is compressed by the reverse strokes of the pistons, the outlet from the cylinders being through sprung-seated outlet valves j^6 (see Fig. 2) opening directly into the chamber j .

The cylinders J' with their pistons and strap connections to the eccentric c constitute a compressor which takes vapor from the vaporizing end B through the hollow shaft C and compresses it in the liquefying end A . Compression is effected by virtue of the fact that the cylinders are prevented by gravity from revolving while the eccentric c revolves with the container.

In addition to the center of mass of the castings J and J' being placed far below the axis, a heavy weight K (see Fig. 3) preferably of lead is attached to the bottom of these castings and aids in resisting the tendency of the castings and cylinders to revolve.

The mechanical heat due to the compression of the SO_2 and the latent heat of vaporization are conducted away through the walls of the container which are preferably made of a good heat conductor, such as bronze. Liquid SO_2 passes out of the chamber j through holes j^{12} in the bottom of the chamber and attains the velocity of the container by friction with the walls aided by wings a^2 which project from the shells a and a' , and takes the form of an annulus at the greatest diameter of the chamber by virtue of the centrifugal force resulting from its rotation with the container.

A close contact of the cylinders j' against the flats j^3 on the casting J' is insured by subjecting the cylinders to the pressure of springs j^8 .

A collector or scoop j^9 mounted on the casting J and which, therefore, does not revolve, projects upwardly to the inner sur-

face of the revolving annulus of liquid and diverts a small stream of the liquid into a receptacle or chamber j^{10} in the casting J when the machine is in motion. The oil which is used for lubricating the working parts is lighter than the liquid SO_2 and therefore lies upon the inner surface of the annulus of liquid so that it is carried by the scoop j^9 into the receptacle or separating chamber j^{10} together with liquid SO_2 . A separation of the liquid SO_2 and oil takes place in the separating receptacle j^{10} , the oil rising to the top and eventually overflowing the lip j^{11} into the chamber j . The collected oil drains out through the apertures j^{12} upon the surface of the revolving annulus of liquid and becomes a part thereof to be again collected by the scoop j^9 and passed over the working parts. This circulation of the oil over the compressor parts effects the required lubrication within the container and the rate of circulation of the oil is dependent upon the area of the apertures j^{12} in the bottom of the chamber j .

The collector or scoop j^9 is formed to provide a closed channel which conducts the entering liquid below the surface of that already contained in the separating receptacle j^{10} avoiding to a considerable extent the foaming and emulsifying of the oil and liquid SO_2 and allowing separation by gravity to more easily and quickly take place.

The liquid SO_2 passes through a screen head j^{13} and rises in a pipe j^{14} which empties into a reservoir j^{15} in the casting J' at the level 100 which the SO_2 assumes under the head of the oil overflowing the lip j^{11} .

It will be noticed that the liquid SO_2 which flows into reservoir j^{15} is practically free of oil and is ready to be conducted to 105 the evaporating end of the container.

A valve j^{16} closes an aperture in the bottom of the reservoir j^{15} , which aperture communicates with the interior of a pipe j^{17} located within the hollow shaft C . The valve j^{16} is closed by the weight of a float j^{18} and is only opened when sufficient liquid SO_2 is present in the reservoir j^{15} to raise the float j^{18} . It will therefore be seen that the valve j^{16} will only permit the passage of liquid SO_2 and will never allow vapor to pass through into the vaporizing end. This arrangement is provided to avoid the transport while the machine is running, of heat by vapor into that portion of the apparatus in which the temperature has been lowered. The pipe j^{17} is rigidly secured to the casting J' adjacent the valve j^{16} and is held with that casting against rotation.

The hollow shaft C projects for some distance also into the interior of the evaporating end B and on this projecting end of the shaft is loosely hung a combined liquid and oil circulator and separator which comprises (see Figs. 6, 7, and 8) a central cast-

ing l which provides the supporting bearing l' resting on the projecting end of the hollow shaft C , a passage l^2 by which vapor from the interior of the vaporizing end 5 B above the shaft C may pass downwardly and into the end of the hollow shaft C , and a passage l^3 by which oil may pass from a separator l^9 upwardly and flow into the end of the hollow shaft C . The pipe l^{17} 10 passes entirely through the casting l and discharges against the wall of the outer shell b' and the casting l is secured to this pipe l^{17} by a key l^4 so that the circulator and separator is held stationary with the 15 pipe l^{17} which is in turn held stationary with the castings J and J' and the weight K in the liquefying end A .

A cylindrical circulating receiver l^5 open at its top is mounted on the casting l which 20 casting forms the bottom of the receiver. A smaller cylindrical separating receiver l^6 is mounted within the receiver l^5 adjacent its forward wall, *i. e.*, that wall toward which the outer shell of the container moves, and 25 the casting l also forms the bottom of this receiver l^6 . A tube l^7 provides communication between the separator receiver l^6 and a separating chamber l^8 below the casting l . This tube l^7 upstands from the bottom of the 30 receiver l^6 to form a pocket l^8 , the purpose of which will presently appear. Two scoops or collectors l^{10} and l^{11} are mounted in tandem on the upper edges of the receivers l^5 and l^6 respectively and extend upwardly 35 to the inner surface of a revolving annulus of liquid in the end B which is similar to that in the end A , being produced by the friction of the liquid against the walls of the container aided by wings b^2 projecting inwardly from the shells b and b' . The collector l^{11} being the foremost of the two deflects a small stream of the liquid from the inner surface of the revolving annulus of liquid into the receiver l^6 , and in view of 40 the fact that some oil unavoidably gets into the vaporizing end B this small stream of liquid will consist of some oil and some liquid SO_2 and it is found in practice that even with the greatest of care some solid 45 impurities appear and these solid impurities being heavier than the liquids will collect in the pocket l^8 and thus be permanently removed from the circulating system. This pocket l^8 also receives the stream of mixed 50 SO_2 and oil and aids in a measure in preventing the formation of a froth. The mixed oil and liquid SO_2 flow down the tube l^7 to a point below the surface of the liquid contained in the separating chamber l^8 , this point being approximately at 55 the static level of the liquid SO_2 when both that liquid and oil are present in the separator. This introduction of the mixed liquid SO_2 and oil at the static level of the SO_2 60 already contained in the separator avoids 65

frothing and emulsifying and aids gravity separation. A distributing pipe l^{12} extends upwardly from the lowermost part of the separating chamber l^8 and passes through the side-wall of this chamber at a point 70 above the lower end of the tube l^7 , this point being located at the level which liquid SO_2 will take in the pipe l^{12} when oil upon the surface outside said pipe rises to the level of and enters the end of the hollow shaft C . 75 The pipe l^{12} discharges against the wall of the shell b .

The collector l^{10} being directly in the rear of the collector l^{11} deflects a small stream of liquid SO_2 alone, the film of oil having been 80 removed by the preceding collector, and directs this liquid into the circulating receiver l^5 from which it flows by a distributing pipe l^{13} against the wall of shell b' . The liquid SO_2 which passes through the circulating receiver l^5 is simply taken from the inner surface of the revolving annulus of liquid and discharged upon the wall of the container near the axis of the machine, the object being to offer by circulation of the SO_2 85 in the vaporizing end more opportunity for the vaporization of the liquid and a greater area of cooled surface than would be given if the refrigerant were brought into contact with this wall but once and in this connection it is important to note that the refrigerant is by means of the velocity of rotation of the container quickly thrown to the outermost portions of the vaporizing end B , where it forms the annulus above referred to. 90

The collectors, especially those characterized at l^{10} and l^{11} are preferably made quite small and V-shaped in cross-section, as it is to advantage in preventing emulsifying of the oil and refrigerant, to scoop a relatively deep thin stratified stream from the liquid annulus so as to avoid the disturbance of and the retarding effect upon the liquid which would be present if a flat or broader scoop were employed. The form of these 105 scoops is of considerable importance in connection with the working of a machine of this type.

A pressure equalizing valve c^{10} mounted to rotate with the hollow shaft C is provided 110 to permit, when open, the compressed vapor in the liquefied end A , to pass directly into the hollow shaft C , and thence to the vaporizing end B . A spring c^{11} tends to open this valve when the machine is at rest and is 115 overcome by the outward throw of weights c^8 supported on pivoted arms c^7 , during the rotation of the container, and the valve c^{10} is held closed. The arms c^7 are L-shaped and are provided with intermeshing gear teeth c^9 to cause them to move together. The valve c^{10} is connected with one of the arms c^7 . The object of this arrangement 120 is to effect a gas exit from, and an equalization of the pressures in, the two ends of the 125 130

5 container when the machine is at rest that the vaporizer may be emptied when desired, and the compressor may not be required to work against pressure at the start, while the two ends of the container will be automatically isolated when the container has approximately reached its normal speed of rotation.

10 The driving shaft D is hollow and is provided near its outer end with a valve plug d^2 which may be screwed shut while a gas-introducing nozzle is connected to the end of the shaft. This nozzle through which gas is introduced into the container is not 15 shown in the drawing as it forms no part of the present invention. The gas having been introduced into the container and the valve plug d^2 screwed shut, the nozzle is removed and a permanent plug d^3 is screwed into the 20 outer end of the shaft d and a melted or plastic sealing material d^4 is applied to effect the final hermetic sealing of the container.

25 In inclosed refrigerating machines of this type, it has heretofore been proposed to avoid the passage of vapor and the lubricant from the liquefying end of the container to the vaporizing end of the container by operating the valve by means of a 30 float being arranged to rise in the liquid SO_2 and fall in the lubricant oil. This arrangement made it necessary for the float to work in the narrow range between the specific gravity of the liquid SO_2 and that of the lubricating oil, a condition requiring a 35 degree of accuracy of adjustment and delicacy of operation which was undesirable in apparatus intended for unattended working for extended periods. In the present device the separating chamber j^{10} has been so placed 40 in connection with the reservoir j^{15} that this reservoir receives the liquid SO_2 practically freed from any mechanically mixed lubricating oil which would collect upon the surface of the liquid SO_2 within the reservoir 45 and therefore the float j^{18} may work within the range between the specific gravity of the liquid SO_2 and that of the vapor of SO_2 which range is of such extent that extreme 50 accuracy of adjustment is unnecessary and there is always present sufficient lifting power within the liquid SO_2 and sufficient weight when the float is surrounded by vapor to effect the operation of the valve with unfailing promptness and security. 55 The liquid SO_2 which enters the reservoir j^{15} and is permitted to pass therefrom into the vaporizing end, nevertheless, contains some of the lubricating oil in what may be 60 considered solution and upon the vaporization of the liquid SO_2 in the vaporizing end this content of the lubricant will be left within the vaporizing end of the container, and must be conducted therefrom back to the liquefying end or its collection in quantity 65 will seriously affect the working of the

machine. Therefore it has been necessary to combine with the separator, reservoir and float actuated valve of the liquefying end, a means for conducting back to the liquefying end the lubricant carried in solution to the 70 vaporizing end.

75 It will be observed that in the organization described a substantial quantity of lubricant, which in practice will ordinarily be sufficient to immerse the working parts of the compressor, is circulated and practically isolated in the compressor end, while the refrigerant in substantial quantity is practically isolated in the vaporizing end and is circulated over the walls thereof, the mutual 80 isolation of the lubricant and the refrigerant being continuously maintained by providing for the segregation and return to the vaporizer of the vaporized and subsequently liquefied refrigerant, while guarding against 85 the flow of free lubricant to the vaporizer and providing for the segregation and return to the compressor of that quantity of lubricant which is necessarily contained in or emulsified with the compressed lubricant. 90

Having thus described our invention what we claim is:

1. In inclosed refrigerating apparatus having a liquefying compartment and a vaporizing compartment and containing a refrigerant in liquid and vapor states and a lubricant, the combination of a refrigerant reservoir within said liquefying compartment having an outlet leading to said vaporizing compartment, a valve arranged in said outlet, a float designed to be positioned by the surface of juncture of liquid and vapor refrigerant in said reservoir and connected with said valve to operate the same to discharge through said outlet only the liquid content of said reservoir, and a separator adapted for the mechanical separation of the lubricant and liquid refrigerant and the discharge of the liquid refrigerant alone into said reservoir, with a second separator within the said vaporizing compartment adapted to receive mechanically mixed liquid refrigerant and lubricating appearing within the vaporizing compartment upon the vaporization of the refrigerant, and means for conveying the mixed liquid refrigerant and lubricant within the vaporizing compartment into said second separator; a conduit for conveying the separated lubricant from said second separator to said liquefying compartment, and a conduit for conveying the separated refrigerant from said second separator to the wall of said vaporizing compartment; substantially as and for the purpose set forth. 115

2. In inclosed refrigerating apparatus having a liquefying compartment and a vaporizing compartment adapted to contain a refrigerant in vapor and liquid states and a lubricant, the combination with- 120

- in the liquefying compartment of a refrigerant reservoir having an outlet leading to said vaporizing compartment, a valve arranged in said outlet, a float designed to be positioned by the surface of juncture of liquid and vapor refrigerant in said reservoir and connected with said valve to operate the same to discharge through said outlet only the liquid content of said reservoir and a separator adapted for the mechanical separation of the lubricant and liquid refrigerant and the discharge of the liquid refrigerant alone into said reservoir; substantially as and for the purpose set forth. 5 70
- 15 3. In inclosed refrigerating apparatus having a liquefying compartment and a vaporizing compartment containing a refrigerant in liquid and vapor states and a lubricant, the combination within the vaporizing compartment of a separator adapted to receive mechanically mixed liquid refrigerant and lubricant, and means for conveying the mixed liquid refrigerant and lubricant collected within said vaporizing compartment into said separator; a conduit for conveying the separated lubricant from said separator to said liquefying compartment, and a conduit for conveying the separated refrigerant from said separator to the wall of said vaporizing compartment; substantially as and for the purpose set forth. 20 80
- 25 4. In a rotary refrigerating apparatus of the character described having liquefying and vaporizing compartments, the liquid contents of which assume the form of an annulus, a non-rotating member within the vaporizing compartment, comprising a collector projecting within the surface of the annulus of liquid, a separator arranged to receive liquid from said collector, a conduit leading from the upper part of said separator to said liquefying compartment for conveying separated lubricant from the separator to the liquefying compartment, a second 30 85 conduit leading from the lower part of the separator and discharging toward the wall of the vaporizing compartment for conveying separated liquid refrigerant from the separator and discharging it upon the side wall of the vaporizing compartment, and a third conduit arranged to receive liquid from said collector and discharge it against the side wall of the vaporizing compartment; substantially as and for the purpose set forth. 40 90
- 45 5. In inclosed refrigerating apparatus having a liquefying compartment and a vaporizing compartment containing a refrigerant in liquid and vapor states and a lubricant, a separator in the liquefying compartment for separating the lubricant from the liquid refrigerant, a reservoir for the separated liquid refrigerant also in said compartment, means for transferring the separated liquid refrigerant from the separator to the reservoir, a conduit for transferring the liquid refrigerant from said reservoir to the vaporizing compartment, and means for returning the vaporized refrigerant from the vaporizing compartment to the liquefying compartment, and for liquefying it therein; substantially as described. 55 100
- 60 6. In inclosed refrigerating apparatus having a liquefying compartment and a vaporizing compartment containing a refrigerant in liquid and vapor states and a lubricant, a separator in the liquefying compartment for separating the lubricant from the liquid refrigerant, a reservoir for the separated liquid refrigerant also in said compartment, means for transferring the separated liquid refrigerant from the separator to the reservoir, a conduit for transferring the liquid refrigerant from said reservoir to the vaporizing compartment, and means for returning the vaporized refrigerant from the vaporizing compartment to the liquefying compartment, and for liquefying it therein, in combination with a second separator within the said vaporizing compartment adapted to receive mechanically mixed liquid refrigerant and lubricant appearing within the vaporizing compartment upon the vaporization of the refrigerant, means for conveying the mixed liquid refrigerant and lubricant within the vaporizing compartment into said second separator, and means for returning the separated lubricant to the liquefying compartment; substantially as described. 65 105
- 70 7. In apparatus of the character described having liquefying and vaporizing compartments, a substantial body of liquid refrigerant maintained in said vaporizing compartment and a separator and circulator adapted to separate lubricant from said body of liquid refrigerant and return said lubricant to said liquefying compartment and to repeatedly bring said liquid refrigerant into contact with the walls of said vaporizing compartment; substantially as described. 75 110
8. Inclosed rotary refrigerating apparatus having liquefying and vaporizing compartments, lubricant circulating appliances designed to substantially isolate and circulate lubricant within said liquefying compartment, a separator and circulator within the vaporizing compartment adapted to separate lubricant from the liquid refrigerant and to discharge the separated liquid refrigerant into the vaporizing compartment upon portions of the end walls thereof from which the refrigerant flows under the centrifugal force to a liquid annulus at the periphery of said compartment, means in the liquefying compartment for separating the liquefied refrigerant and returning it to the vaporizing compartment, and a lubricant replacement device adapted to return to the liquefying compartment the separated lubricant substantially as described. 80 115
- 90 9. In inclosed refrigerating apparatus having a liquefying compartment and a vaporizing compartment containing a refrigerant in liquid and vapor states and a lubricant, a separator in the liquefying compartment for separating the lubricant from the liquid refrigerant, a reservoir for the separated liquid refrigerant also in said compartment, means for transferring the separated liquid refrigerant from the separator to the reservoir, a conduit for transferring the liquid refrigerant from said reservoir to the vaporizing compartment, and means for returning the vaporized refrigerant from the vaporizing compartment to the liquefying compartment, and for liquefying it therein, substantially as described. 95 120
- 100 10. In inclosed rotary refrigerating apparatus having liquefying and vaporizing compartments, lubricant circulating appliances designed to substantially isolate and circulate lubricant within said liquefying compartment, a separator and circulator within the vaporizing compartment adapted to separate lubricant from the liquid refrigerant and to discharge the separated liquid refrigerant into the vaporizing compartment upon portions of the end walls thereof from which the refrigerant flows under the centrifugal force to a liquid annulus at the periphery of said compartment, means in the liquefying compartment for separating the liquefied refrigerant and returning it to the vaporizing compartment, and a lubricant replacement device adapted to return to the liquefying compartment the separated lubricant substantially as described. 105 125
- 110 11. In inclosed rotary refrigerating apparatus having liquefying and vaporizing compartments, lubricant circulating appliances designed to substantially isolate and circulate lubricant within said liquefying compartment, a separator and circulator within the vaporizing compartment adapted to separate lubricant from the liquid refrigerant and to discharge the separated liquid refrigerant into the vaporizing compartment upon portions of the end walls thereof from which the refrigerant flows under the centrifugal force to a liquid annulus at the periphery of said compartment, means in the liquefying compartment for separating the liquefied refrigerant and returning it to the vaporizing compartment, and a lubricant replacement device adapted to return to the liquefying compartment the separated lubricant substantially as described. 115 130

fying compartment the lubricant separated in the vaporizing compartment; substantially as described.

9. Inclosed rotary refrigerating apparatus having a liquefying compartment in which the refrigerant is compressed and cooled to liquefy it, and a vaporizing compartment to which the liquid refrigerant is supplied from the liquefying compartment and in which the refrigerant assumes the form of an annulus at the periphery of the compartment, in combination with means within the vaporizing compartment for taking up the refrigerant therein and discharging it without the compartment upon portions of the end walls thereof from which the refrigerant flows under centrifugal force to the said annulus, whereby the refrigerant is repeatedly circulated upon the walls of the vaporizing compartment; substantially as described.

10. Inclosed rotary refrigerating apparatus having liquefying and vaporizing compartments, lubricant circulating appliances designed to substantially isolate and circulate lubricant within said liquefying compartment, means for returning the liquid refrigerant to the vaporizing compartment in which it assumes the form of an annulus at the periphery of the compartment, means for taking up the surface layer of said annulus and for separating lubricant therefrom, means for discharging the liquid refrigerant from which the lubricant is so separated again into the vaporizing compartment, and means for taking up a sub-surface layer of said annulus and discharging it within the vaporizing compartment upon portions of the end walls thereof from which the refrigerant flows under centrifugal force to the said annulus; substantially as described.

11. In apparatus of the character described, a rotary vaporizing compartment having an oil separator and refrigerant circulator comprising a substantially stationary receptacle carrying a plurality of tracking collector fingers, a separating compartment within the receptacle and to which the mixed lubricant and refrigerant collected by the

leading collector finger is conducted, a conduit for the separated lubricant from said compartment to the liquefying compartment, a second conduit for conducting the separated refrigerant to the wall of the vaporizing compartment, and a conduit by which the liquid collected by the tracking collector finger is conducted to the wall of the vaporizing compartment; substantially as described.

12. In apparatus of the character described a rotary vaporizing compartment in which the liquid refrigerant and lubricant will assume the form of an annulus, a lubricant separator, means for removing the outer layer of the annulus and conducting it to the separator, a conduit for returning the separated lubricant to the liquefying compartment, a second conduit for returning the separated refrigerant to a portion of the wall of the vaporizing compartment from which it will flow to the annulus under the impulse of centrifugal force and means for removing an inner layer of the annulus and conducting it to a portion of the wall of the vaporizing compartment from which it will flow to the annulus under the impulse of centrifugal force; substantially as described.

13. In refrigerating apparatus, the combination with rotatable container of substantially stationary channeled collector scoops within said container projecting outwardly and terminating adjacent the peripheral wall of said container in an open-ended mouth V-shaped in cross-section.

14. In refrigerating apparatus of the character described, the combination with the rotatable container and separator therein of a collector-scoop having a V-shaped mouth and mounted to convey liquid from adjacent the periphery of said container to said separator.

In testimony whereof we affix our signatures, in presence of two witnesses.
